CLAIM

The ornamental design for a high security locking display case, as shown and described.

DESCRIPTION

FIG. 1 is a perspective view of a high security locking display case.

FIG. 2 is a perspective view of the high security locking display case with doors open.

FIG. 3 is a front view thereof;

FIG. 4 is a back view thereof;

FIG. 5 is a left side view thereof;

FIG. 6 is a right view thereof;

FIG. 7 is a top view thereof; and,

FIG. 8 is a bottom view thereof.

The broken lines indicate portions of the article that form no part of the claimed design.
